United States Patent Office

Des. 228,478

Patented Sept. 25, 1973

228,478

LOCK ON TAG

Sadayoshi Yonai, Tokyo, Japan, assignor to
Imaizumi Co., Ltd., Tokyo, Japan

Filed Sept. 17, 1971, Ser. No. 181,650

Term of patent 14 years

Int. Cl. D20—99

U.S. Cl. D96—8 A

FIG. 1

FIG. 4

FIG. 5

FIG. 2

FIG. 3

FIG. 1 is a front elevational view of a lock on tag showing my new design;

FIG. 2 is a rear elevational view thereof;

FIG. 3 is side elevational view taken from the right of FIG. 1;

FIG. 4 is a top plan view; and

FIG. 5 is a bottom plan view.

I claim:

The ornamental design for a lock on tag, substantially as shown.
